UNITED STATES PATENT OFFICE.

EDWIN JOSEPH LESTER AND WILLIAM GEORGE BEST, OF CLAPHAM, ENGLAND.

AIR-SHIP AND AEROPLANE.

946,678.

Specification of Letters Patent. Patented Jan. 18, 1910.

Application filed February 23, 1909. Serial No. 479,389.

To all whom it may concern:

Be it known that we, EDWIN JOSEPH LESTER and WILLIAM GEORGE BEST, subjects of the King of Great Britain and Ireland, residing at Clapham, in the county of Surrey, England, have invented new and useful Improvements in and Relating to Air-Ships and Aeroplanes, of which the following is a specification.

10 This invention relates to means for propelling, raising, lowering and steering airships and aeroplanes, and consists of improvements in that type of mechanism in which use is made of fans or paddle wheels 15 contained within rotatable casings provided with sector-shaped openings.

According to our invention we provide the car of an airship or aeroplane with two or 20 more pairs of fans or paddle wheels which are contained within rotatable casings provided with sector-shaped openings. We control movement of the airship or aeroplane in all directions by suitably adjusting the 25 positions of the openings in the pairs of casings and effect steering by swiveling the fans and casings.

By means of our invention we are able by 30 suitably adjusting the positions of the openings in the casings not only to reverse the direction of movement of an airship without reversing the motor but also to cause it to rise and fall at will. Further in the case of 35 an airship provided with a gas bag the car is always in a horizontal position and the airship will rise and fall vertically. Moreover the ballast which has in the case of other airships to be carried and discharged when the airship has to rise is dispensed with and the amount of gas in the gas bag 40 is practically always the same as it is not necessary to allow it to escape when the airship has to fall, rising and falling of the airship in our case being effected by altering the positions of the openings in the casings.

45 In carrying out our invention we provide the car of an airship or aeroplane with two or more pairs of fans or paddle wheels each of which has four or more blades. Said blades are secured to the outer peripheries 50 of drums, and the blades and drums closely fit the interiors of rotatable casings, the spaces intervening between the peripheries of the drum and the interiors of the casings forming air chambers. Sector-shaped openings, 55 preferably extending along one third of their circumferences, are made in the cas-

ings to allow of the entrance and expulsion of the air. The pairs of casings are moved so as to vary the positions of their openings, and thus determine the direction of the movement of the airship or aeroplane, and the drums and casings are swiveled, so as to effect turning, by any suitable mechanism, which is preferably constructed in the manner hereinafter described.

In order that our invention may be thoroughly understood we will now refer to the accompanying drawings illustrating the application thereof.

Figure 1 is a side elevation and Fig. 2 is 70 a plan illustrating our invention applied to the car of an airship. Fig. 3 is a part section and part elevation showing, on an enlarged scale, an arrangement of joints and other parts which we have devised for the purpose of enabling the pairs of fans or paddle wheels and their casings to be simultaneously swiveled and the casings to be moved around the fans or paddle wheels according to the desired direction of movement. Figs. 4 to 11 are diagrams showing the positions to which the casings are simultaneously rotated according to the direction of movement required, the latter being indicated by the arrows at the centers of the figures.

According to our invention we provide the car 1 with two or more pairs of fans or paddle wheels, each of which fans or wheels 90 consists of a drum 2 and four or more blades 3, which closely fit the interiors of rotatable casings 4. The casings 4 are provided with sector-shaped openings 4', which act as inlets and outlets for the part-annular 95 spaces or chambers intervening between the peripheries of the drums and the interiors of the casings. Said openings 4', which are preferably of the shape shown, extend along one third of the circumferences of the casings. When two pairs of fans or paddle wheels are employed, as shown, the openings 4' in the casings of the two pairs of fans or wheels are preferably arranged so as to face opposite ways so as to prevent the currents 105 of air produced by one pair of fans or wheels interfering with those produced by the other pair. The shafts supporting the fans or paddle wheels are divided into three parts, a central part 5 and two outer parts 6. The 110 central parts 5 are connected at their outer ends to the outer portions 6 of the shaft by

means of universal joints 7. The fans or paddle wheels are driven by means of a suitable motor 8, driving connection between the motor 8 and the central parts 5 of the 5 shafts of the fans or paddle wheels being effected by any suitable means, such as a flanged or grooved pulley 9 fixed to the shaft of the motor, belts 10 and 10', and pulleys 11 secured to the central parts 5 of the 10 said shafts. When the openings in the casings are arranged in the manner described above and shown on the drawings open and crossed belts 10 and 10' are used. The casings 4 are secured to the outer ends of 15 sleeves 12 which are arranged so as to rotate within swiveling arms 13. The swiveling arms 13 are supported in bearings 14 carried by the framework of the car and are provided with steering arms 15. The 20 steering arms 15 of each pair of wheels are connected together by means of rods 16 which are simultaneously actuated, so as to swivel the casings 4, by any suitable arrangement such as that shown in Figs. 1 25 and 2, where 17 is a steering wheel which actuates an arm 18 connected by suitable cords 19 to arms 16' on the rods 16.

To enable the casings 4 to be simultaneously rotated to an equal extent around the fans or paddle wheels we prefer to use the following construction and arrangement of parts. The inner ends of the sleeves 12 are secured to the movable parts 20 of swiveling joints the other or relatively fixed portions 35 21 of which are connected by arms 22 to chain wheels 23. The chain wheels 23 are carried by bushings 24, which serve as supports for the outer ends of the central parts 5 of the shafts carrying the fans or paddle 40 wheels. The chain wheels 23 may either rotate on the bushings 24, in which case the latter would be fixed to the frame of the car, or the wheels may be secured to the bushings, which would then rotate in bearings 45 provided in the frame of the car. The chain wheels 23 are connected to and the casings 4 are rotated by any suitable means within easy reach of the occupant of the car. Such means may consist, as shown in Figs. 1 and 50 2, of a wheel 25 fixed to a horizontal shaft 26, the rotation of which is transmitted to the chain wheels 23 by means of the chain wheels 27 and lengths of chain 28 engaging the chain wheels 27 and connected 55 by wire ropes 29 to similar lengths of chain 30 engaging with the chain wheels 23. Suitable devices, not shown, are provided for keeping the chains taut, such as turn-buckles and eyes.

60 Instead of using chain wheels as above de-

scribed flanged pulleys and wire ropes, fastened at one point to said pulleys, may be employed. Again, instead of forming the fans or paddle wheels of blades secured to the peripheries of drums, as shown in the 65 drawings, each fan or wheel may consist of blades secured to the edge of a disk, the central portions of the sides of the casings being carried inward to form the part-annular air spaces or chambers above referred to. 70

Figs. 4 to 11 show the positions to which the openings in the casings must be rotated in order to move the airship or aeroplane in the directions indicated by the central arrows.

75

Having now described our invention what we have discovered and desire to secure by Letters Patent of the United States is:—

1. In airships and aeroplanes, provided with mechanism of the type specified herein, means for effecting the propulsion, raising and lowering thereof consisting of fans or paddle wheels connected together in pairs and contained within casings provided with sector-shaped openings and adapted to be 80 simultaneously rotated to an equal extent, substantially as described herein.

2. In airships and aeroplanes, provided with mechanism of the type specified herein, means for effecting the propulsion, raising, 85 lowering and steering thereof consisting of fans or paddle wheels connected together in pairs and contained within casings provided with sector-shaped openings and adapted to be simultaneously rotated and also swiveled, 90 substantially as described herein.

3. In airships and aeroplanes, provided with mechanism of the type specified herein, the combination of fans or paddle wheels connected together in pairs, coupled to the 100 central portions of their shafts by means of universal joints and supported at their outer ends within swiveling arms connected together in pairs, casings surrounding the fans or paddle wheels, provided with sector-shaped openings, adapted to swivel with the fans or paddle wheels and to be rotated around the latter, and means for rotating the casings and means for swiveling the fans or paddle wheels and the casings, substantially 105 110 as described herein.

In testimony whereof we have signed our names to this specification in the presence of two subscribing witnesses.

EDWIN JOSEPH LESTER.
WILLIAM GEORGE BEST.
